UNITED STATES PATENT OFFICE

2,416,372

FIBRE CONTAINER

Horace C. Brown, Orinda, Calif., assignor to
 Rheem Manufacturing Company, Richmond,
 Calif., a corporation of California

Application January 21, 1944, Serial No. 519,167

3 Claims. (Cl. 229—5.7)

1

The invention relates to a fibre container, and particularly to a fibre container provided with a metal part with which the container closure or other means may cooperate for securing the closure to the container.

An object of the invention is to provide a fibre container which will have all of the effectiveness and adaptability of a metal container for closure application, attachment and sealing.

Another object of the invention is to provide a fibre container having a closure anchoring part which is located entirely on the exterior of the container, and may be effectively secured to the walls of the container without the use of fastening means piercing the fibre.

A further object of the invention is to provide a fibre container having a metal closure-anchoring part provided therein, in which said part and the adjacent portions of the fibre walls are so designed and arranged in relation to each other, that while such metal part will provide for the anchoring or fastening of the closure to the container, the relatively yielding fibre wall portions will provide the seat for engagement by the closure so as to thus dispense with the need of gaskets for insuring a proper seating or sealing of the closure on the container.

The invention possesses other objects and features of advantage some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to said drawings:

Figure 1 is a fragmentary side view of a container constructed in accordance with the present invention, portions being removed to disclose hidden parts.

Figure 2 is a full longitudinal sectional view of the container as shown in Figure 1.

Figure 3 is an enlarged fragmentary detail of a portion of the container shown in Figure 2.

Figures 4 and 5 are views similar to Figure 3 but showing somewhat modified arrangements.

In the embodiment of the invention here illustrated, the container is formed with cylindrical side walls 6 preferably made up of laminations 7 of fibre or the like. At an end of the walls is provided an opening 8 arranged to be covered by a closure 9 which, as shown in Figures 2 and 3, is made up of laminations 12 of material

2

similar to the laminations 7. The cover is formed with an inset body portion 13 and an annular skirt 14 which extends from the edge of the body 13 and is arranged to engage the portion 16 of the inner side of the walls 6, it being thus noted that since the portion 16 is a part of the fibre wall of the container, a more or less yielding seat for the closure will be provided.

10 To form a means on the walls of the container to which the closure may be anchored when the latter is operatively engaged in the opening 8, there is provided a band 17 preferably of sheet metal which extends continuously around and embraces the container on the exterior side of the walls 6 adjacent the opening. The outer longitudinal portion of the band 17 is extended first radially outwardly thence longitudinally inwardly and thence radially inwardly to form a 20 curl or roll 18 lying radially outwardly of what may be termed the body portion 19. Desirably the outward longitudinal part 21 of the seat 16 is flared radially outwardly corresponding to the adjacent portion of the band, and is gradually 25 reduced in section so that said part 21 will curve over and merge into the curl 18. This construction provides a smooth, protected, and reinforced rim for the container at the opening, and at the same time facilitates the ready and proper insertion of the closure in its seat. If desired, the longitudinally outer part 22 of the skirt 14 may be flared and tapered in correspondence with the part 21 of the container walls, and is preferably extended so as to fit well over said part 21.

30 For securing the band on the walls against longitudinal displacement in opposite directions, there is rolled or otherwise depressed into the side of the walls 6, an inwardly offset portion 23 completely around the container, and preferably such offset is fitted or extruded into a groove 24 provided in the outer side of the walls and desirably formed therein simultaneously with the offset 23. As an additional means of fastening the band and container together, a film of 40 water-proof glue is interposed between the opposing surfaces of the band and container throughout the entire area of engagement. It may be noted that the lip or part 21 also assists 45 in locking the band in position, and preferably the longitudinally inner edge 26 is crimped inwardly into the wall stock as a further attachment for the band and to present a smooth surface at the juncture of such edge and the walls. 50 For fastening or locking the closure 9 in oper-

ative position in the seat on the container, there is here shown a metal clamping ring 27 which extends over the end parts of the closure and container walls and is compressed around the curl or roll 18 of the band, a portion 28 of the ring being arranged to extend longitudinally along the body of the band. Desirably the portion 28 of the ring and a part of the contiguous portion arranged to engage the curl, is slotted so as to provide a plurality of tongues 29 and thus permit the more ready application of the ring over the closure and container parts and the removal of the ring from engagement therewith.

If desired the container of my invention may be used with a metal closure 31 such as shown in Figure 4, in place of the fibre closure illustrated in Figures 1 to 3. The same type of clamping ring 27 may be utilized with such metal closure, or if preferred, the ring may be incorporated as at 32 as an integral part of the metal closure 33 shown in Figure 5.

It will now be clear that in all of the embodiments illustrated, the cooperating members for fastening and anchoring the closure in position on the container, are formed of material such as metal, whereas with respect to the parts which provide for the engagement of the closure and the container, at least one of such parts is formed of a relatively yielding material such as fibre. In this manner a fastening arrangement of maximum strength and resistance will be had, and at the same time an effective engagement and seal will be afforded between the closure and container without the addition of any separate gasket or other sealing aid. It will also be noted that with the closure anchoring arrangement of my invention, no part of the metal on the container is exposed to the interior of the container, smooth pouring from the container is permitted and none of the contents may leak back into the container through the joints between the attached parts.

I claim:

1. In a container having cylindrical side walls of fibre or the like and providing inwardly of an end thereof a cylindrical closure seat, a metal band surrounding and embracing said walls ad-

5 jacent said end and having an annular outer portion forming a curl positioned radially outwardly from said walls and adjacent said open end, a closure fitting within said seat and having a portion extending therefrom and overlying but not encircling said curl, and means independent of said closure and band securing said closure to the curl.

2. A container having fibre side walls and an opening at an end with the adjacent end portions of the walls flared outwardly thereat, a band of sheet metal provided with a body embracing said walls and having a circumferential flared portion corresponding to and embracing the flared portion of said wall, said band being extended from said flared portion radially outwardly and thence longitudinally inwardly and thence radially inwardly to said body, said flared portions cooperating to hold the band against longitudinally inward displacement on the container, and means, independent of and supplemental to said flared portions for locking said band to the container against longitudinally outward displacement thereon.

3. A container in accordance with claim 1, characterized by the flared portion of the walls being of decreasing thickness from its inner to its outer end, and having such outer end and the longitudinally outermost point of said band extension in substantial alignment transversely of the container.

HORACE C. BROWN.
